UNITED STATES PATENT OFFICE.

QUINCY A. TOWNES, OF LYNN, MASSACHUSETTS.

MACHINE FOR NAILING HEEL-LIFTS.

SPECIFICATION forming part of Letters Patent No. 276,648, dated May 1, 1883.

Application filed February 13, 1883. (No model.)

To all whom it may concern:

Be it known that I, QUINCY ADAMS TOWNES, of Lynn, in the county of Essex, of the Commonwealth of Massachusetts, have invented a new and useful Improvement in Machinery for Pressing and Nailing Shoe or Boot Heels; and I do hereby declare the same to be described in the following specification and represented in the accompanying drawings, of which—

10 Figure 1 is a top view, Fig. 2 a front elevation, and Fig. 3 a vertical median and transverse section, of a machine embodying my invention, the nature of which is defined in the claim hereinafter presented. Fig. 4 is a perspective view of a pack of heel-lifts as arranged for being pressed and nailed together, preparatory to which they are to have a suitable cement applied to their surfaces which are to be in contact.

20 In the drawings, A denotes the machine-frame, provided on its top with a recess, B, to receive a pack of heel-lifts to be pressed and nailed. Extending down from the said recess is a passage or tube, C, having within it a 25 plunger or nail-driver, D, which at its lower end is pivoted to the shorter arm of a lever, E. A rod, F, provided at its upper end with a head, a, goes down through the plate b of the frame, and at its lower end is pivoted to the 30 longer arm of the lever E. The said lever is fulcrumed to an upright, e, to which and to the shorter arm of the lever a spiral spring, d, arranged as shown, is affixed. In front of the tube C is another plunger, or what may be 35 termed the "ejector," G, which is arranged to move upward into the heel-lift-receiving recess, and is pivoted to the shorter arm of another lever, H, fulcrumed to another upright, I, to which and the said arm a spiral spring, e, 40 is fixed, and is arranged as represented. A rod, K, provided at top with a head, f, and adapted to slide vertically in the plate b, is at its lower end pivoted to the longer arm of the lever H. Furthermore, above the heel-lift-receiving recess is a platen or presser, L, which is fixed 45 to the upper end of a vertical rod, M, that at its foot is pivoted to a pedal, N, arranged as shown, the same being so as to allow of the rod being revolved in the pedal and within 50 the plate b. A spiral spring, O, arranged on the rod M and between the presser L and the

plate b, serves to force the rod, presser, and pedal upward after a depression of the pedal by the foot of an attendant may have taken place.

55

In using the machine a person is first to drop a nail head foremost into the tube C, at its upper end, the nail going entirely below the heel-lift-receiving recess, after which the pack of heel-lifts, having cement in a soft or moist state between the several lifts, is to be placed in the heel-lift-receiving recess, so as to be directly over the tube C and the ejector G. Next, the presser L is to be turned around so as to come immediately over the 60 pack, and by moving the pedal downward is to be depressed upon the said pack, so as to firmly condense it or force its lifts into close contact. While the presser is so in action on the pack the attendant is with his right hand 65 on the knob or head a to press the rod F downward, and thereby cause the nail-driver D to force the nail upward through the several lifts. This having been accomplished, the attendant is to remove his hand from the head 70 a and his foot from the pedal, in order to allow the spring O to elevate the presser of the pack, and the spring d to operate to draw the nail-driver downward in the tube C. Next, the attendant is to turn the presser around 75 from over the pack, and should force downward the rod K, so as to cause the ejector G to be pressed upward against the pack and force it out of the heel-lift-receiving recess or upward therein, as occasion may require. 80

85

This machine has been found in practice very efficient and advantageous for preparing a heel-pack for the machine generally employed for dressing it and nailing the lifts thereof together near the dressed edges.

90

I claim—

The machine, substantially as described, consisting of the heel-lift-receiving recess, the nail-receiving passage or tube and its plunger, the ejector, and the presser arranged in or applied to the frame, and having to the said plunger, ejector, and presser, mechanisms, essentially as specified, for operating them, as explained.
